ELASTICALLY CONNECTED MINE CAR BUMPER

Herman H. Pancake, Huntington, W. Va., assignor to American Car and Foundry Company, New York, N. Y., a corporation of New Jersey

Application May 25, 1937, Serial No. 144,605

20 Claims.

(Cl. 213—9)

This invention relates to improvements in bumpers and draft members in general and in particular to such devices for use on mine or other industrial cars.

One object of the invention is to provide a bumper and draft element which is connected to the car body by means of a non-metallic cushioning material acting in shear to resist the buffing and draft forces.

A further object of the invention is the provision of a combined draft and buffing element connected to the car structure by means of non-metallic cushioning means and so arranged as to occupy the space now taken by the present wooden type bumper in certain classes of cars.

A still further object of the invention is the provision of a combined buffing and draft element connected to the car structure by means of a non-metallic cushioning element and so arranged as to be completely protected from injurious material.

These and other objects of the invention will be apparent to persons skilled in the art from a study of the following description and accompanying drawings, in which:

Figure 1 is a plan view of one form with parts broken away to more clearly disclose the connection between the buffing element and car structure;

Fig. 2 is a sectional view taken substantially on line 2—2 of Fig. 1;

Fig. 3 is a sectional view taken substantially on line 3—3 of Fig. 1;

Fig. 4 is a plan view similar to that shown in Fig. 1 but disclosing a modification thereof taken substantially on line 4—4 of Fig. 6 and which is admirably suited to cars having widely spaced sills or of the sill-less type;

Fig. 5 is a sectional view taken substantially on line 5—5 of Fig. 4;

Fig. 6 is a sectional view taken substantially on line 6—6 of Fig. 5;

Fig. 7 is a sectional view similar to Fig. 2 but showing a further modification thereof;

Fig. 8 is a sectional view taken substantially on line 8—8 of Fig. 7, and

Fig. 9 is a sectional view taken substantially on line 9—9 of Fig. 7.

Referring now to the drawings in detail, it is seen that the car is formed with side sills A of suitable cross section which support the car floor B. The sills are in turn connected by suitable bumper carrying end construction C to which may be connected if desired the car end wall E. In the form shown in Figure 4 the bumper carrying construction is not joined to the sills but directly to the floor as will be more fully described later.

The bumper carrying end construction C of Figs. 1 to 3 is constructed as follows: The central floor portion is extended as at 2 to the ends

of the sills as clearly shown and has attached thereto at a point rearwardly of the sill ends an angle member 4. This angle member has a lower horizontal leg 6 secured to the floor, while the vertically directed leg 8 is secured to the sill flanges by means of angle clips 10, thus forming with the sills and extended floor an open pocket in which the bumper element may be secured. This pocket is closed at the top by means of a plate or an upper horizontal portion 12, a rear downwardly directed flange 14 adapted to be welded or otherwise secured to the angle leg 8 and downwardly directed flanges 16 at the sides adapted to overlie and be secured to the side sill webs as clearly shown in Figs. 1 to 3 and 7 to 9. The forward edge of this plate is secured to the end walls by means of an angle member 18, the ends of which are preferably directed downwardly and secured to the sill by means, such as 20, which are of sufficient length to secure a short angle 22 on the inner side of the sills and between the floor extension and end sheet as clearly shown in Figs. 1 and 9. With the type of bumper shown it has been necessary to slot the plate 12 as at 24 in order that the coupling element may move relative to the plate and car structure. With this construction it is seen that the bumper element is completely housed and protected from the lading except for the slot 24 which is closed by the bumper element as is obvious in Figs. 2 and 7.

The combined bumper and draft element of Figs. 1 to 3 is preferably formed as a casting of general box formation having upper and lower plates 26 and 28 joined at the sides by walls 30, at the rear by wall 32 and adjacent the front edge by wall 34. Each of the side and end walls of this member are suitably braced by gussets, such as 36, and the lower plate is provided with openings 38 by means of which access may be had to the interior of the box member. The upper and lower plates and side walls are extended to form a pocket in which wooden blocks 40 of the customary type may be inserted and protected by means of the pressed U-shaped bumper cap 42. The rearwardly directed flanges of the bumper cap are secured to the casting by suitable means, such as bolts 44, which extend through slots in the flanges of the bumper cap as is customary. The upper wall of the bumper member is formed with an upwardly and outwardly inclined projection 46 terminating in an outwardly directed extension constituting a drawbar 48 which is formed adjacent its outer end with an opening 50 adapted to receive a coupling pin (not shown). The coupling pin will have the lower and intermediate portions extending through holes 52 and 54 formed in the upper and lower walls respectively of the casting. The outer surface of the side walls is formed with a positioning projection 56 and with a stop

projection 58, the latter of which is adjacent the point of union between the side wall and rear wall of the casting while projection 56 is adjacent the front wall 34, this arrangement providing a pocket in which inner plate 60 of a resilient unit D may be secured by suitable means, such as bolts 62. It should be noted that the stop and projection form shoulders which will take the entire strain applied by the plate 60, thus relieving the bolts or securing means of any shearing action. The inner plate 60 has vulcanized thereto one side of a block 64 of some non-metallic elastic material such as rubber and the other side of the block is vulcanized or suitably secured to an outer metallic plate 66. The plate 66 is of sufficient length to abut the angle leg 8 and the leg of the front stub angle 22, thus relieving the securing means 68 of any shearing strain. In the instance shown the securing means 68 are bolts having countersunk heads and extend only through the sill and plate 66. Rigid stops 70 are welded or otherwise secured to the outer plates 66 and form stops adapted to cooperate with the stops 58 of the bumper to limit outward movement thereof on draft. It is obvious that inner movement of the bumper will be limited by the striking of rear wall 32 of end construction C against leg 8 of the rear angle.

The bumper shown in Figs. 7 to 9 is almost identical with that just described with the exception that it is adapted for construction from standard plate and rolled sections. In this form the sides of the bumper are formed by channels 72 having inwardly directed flanges to which the upper and lower plates 74 and 76 are secured. The upper plate has its rear edge directed downwardly as at 77 to be welded to the lower plate, thus forming the rear wall of the bumper and forming a stop for the rear end portion of the bumper blocks, the outer edge of which will be in engagement with the bumper cap. In this bumper provision is made for draft by riveting or otherwise securing to the top plate 74 a lower bar 78 and an upper bar 80, the latter of which is bent upwardly and outwardly as at 81 to receive a coupling pin and link (not shown). Plate unit positioning projections 84 and 86 are welded or otherwise secured to the outer surfaces of the channel webs and will receive therebetween the resilient unit plate 60. It is to be noted that the projection 86 is of sufficient length as to strike the flange of stub angle 22, thus limiting the outward movement of the bumper element during application of draft forces. The remainder of the construction illustrated in these figures is substantially identical with that shown in Figs. 1 to 3 and accordingly similar reference numerals have been applied.

In assembling the constructions shown in Figs. 1 to 3 and 7 to 9 inclusive the end pocket will be fabricated on the car, after which the combined draft and bumper element with the resilient units securely attached thereto, but with the bumper cap off, will be lowered into this pocket. It is to be noted that there is sufficient clearance between the end sheet and coupler projection and between the angle 18 and floor sheet extension 2 to permit of such entrance of the coupler and buffer unit. After the unit has been lowered into position the securing means 68 are applied, thus anchoring the plate 66 to the sills and preventing any movement of the bumper unit without stressing the non-metallic material. As soon as the units are secured in position the top cover plate 12 is slid

into position and securely fastened by any suitable means, such as welding, to the sill, rear angle and front angle 18, if desired. With the parts in this condition the bumper blocks may be inserted and the bumper cap secured in position, after which the device is ready for use. It is obvious that any draft force applied will move the entire bumper unit outwardly, thus placing the non-metallic material in shear and this material will accordingly resist the movements of the bumper and coupling element.

In the form shown in Figs. 4 to 6 inclusive the combined bumper and coupling element has been formed more in the nature of a drawhead and as shown is provided with a curved buffering face 90 from which rearwardly converging side walls 92 extend to merge with longitudinal side walls 94. Upper wall 96 is formed integral with the buffering face 90 and the side walls 92 and 94, thus forming an element of substantially channel-shape cross section. In the instance shown this channel is braced by a transverse intermediate wall 98 and a lower horizontal wall 100, thus forming a shank portion to the rear of wall 98 which is of box section. The outward surfaces of the side walls 94 are formed with spaced projections 102 and 104 adapted to receive therebetween an inner metallic plate 106 which is suitably secured in position between the projections by means of bolts or other means 108. These securing means may be placed in position by an operator working through the open end of the box section end as will be obvious in consideration of Figs. 4 and 5. In order that the drawhead may be used for draft a coupler projection 110 is provided extending upwardly and outwardly from the upper wall of the buffering head to receive a coupling pin (not shown).

The inner plate 106 has vulcanized or otherwise secured thereto one side of a block of non-metallic material 112, the other side of which is vulcanized or otherwise secured to an outer plate 114, which will be suitably secured by means, such as 116, to the side walls of the housing element now to be described. The housing element is preferably formed as a pressing with top wall 118, side walls 120 and rear wall 122. The edges of the side and rear walls and the forward edge of the upper wall are flanged laterally as at 124 in order that the housing may be secured to the floor and end wall of the car. The housing rests directly upon the one piece floor sheet and in order to stiffen the construction an outer plate is provided having an inwardly directed flat portion 126 underlying the floor and secured to the floor and housing by common means, such as rivets 128. The forward edge of this plate is directed upwardly as at 130 outside of the end wall and rigidly secured to the end wall as well as to the flanges of the housing by suitable means, such as rivets 132. It is, of course, necessary, in order to permit movement of the drawhead, as well as application of this plate, that it be slotted as at 140, the slot being of such width to permit free movement of the drawhead shank. It is thus seen that a housing is formed of relatively strong material and that this housing is in the form of a box completely closed except for the small opening through which the coupler shank extends.

In order to assemble this construction the drawhead element with resilient units attached is slid inward through the end sheet which is notched sufficiently to permit passage of the entire assembly after which the upper pressed housing is lowered into position and the securing means 116

applied; at the same time, if desired or necessary, the housing may be prevented from shifting relative to the car by applying the rivets 142. With the parts in this position the lower angle plate is slid upwardly over the coupler drawhead shank, after which the rivets 128 and 132 may be driven, thus securely holding the parts in their assembled condition. It is to be noted that the outer plate 114 is of sufficient length to have bearing against the back wall of the housing and against the vertically directed leg 130 of the outer plate member, while projections 104 are of sufficient length as to strike this plate upon excessive outward movement of the drawhead. It is obvious that the non-metallic units are completely protected and that any injurious oils or other foreign element cannot gain access to this housing.

In each of the modifications described any movement of the bumper and coupling element will be resisted by the non-metallic material acting in shear and this material cannot be loaded beyond the limit since suitable stops are provided both for draft and buffing forces. It is evident that with the bumper and coupling element moving longitudinally of the body the resilient units will be subjected to pure shear and that under a combination of lateral and longitudinal, or angular, movements the units will act in shear to resist the movement and will act in compression to resist the pure lateral component. In other words, the units may be said to act in shear to resist the lateral and/or angular movements of the bumper and coupler unit and in compression to resist lateral movements. In each of these forms also the area of the non-metallic material may be readily increased to take care of cars and loads of various sizes, since it is obvious that instead of bolts machine screws could be used with the ends projecting into the openings in the non-metallic material.

While the invention has been described in more or less detail, it is obvious that various modifications other than those mentioned will be apparent to persons skilled in the art and all such modifications are contemplated as fall within the scope of the following claims:

What is claimed is:

1. In combination, a vehicle body construction comprising in part, spaced upright walls rigid with the vehicle body, a substantially horizontal lower supporting plate connecting said upright walls, bumper and coupling means supported on said lower plate for movement relative thereto, and non-metallic cushioning elements secured to said means and to said upright walls and acting in shear to resist longitudinal movements of the said bumper and coupler means and in compression to resist lateral movements thereof.

2. In combination, a vehicle body construction comprising in part, spaced upright walls rigid with the vehicle body, a substantially horizontal lower supporting plate connecting said upright walls, bumper and coupling means supported on said lower plate for movement relative thereto, said means being formed with upright walls located in spaced relation to said first mentioned upright walls, and non-metallic cushioning elements secured to said upright walls and acting in shear to resist longitudinal movements of the said bumper and coupler means and in compression to resist lateral movements thereof.

3. In combination, a vehicle body construction comprising in part, spaced upright walls rigid with the vehicle body, a substantially horizontal

lower supporting plate connecting said upright walls, bumper and coupling means supported on said lower plate for movement relative thereto, said means being formed with upright walls located in spaced relation to said first mentioned upright walls, plates removably secured to said upright walls, and non-metallic cushioning material secured to said plates and acting in shear to resist longitudinal movements of the said bumper and coupling means, said non-metallic cushioning material acting in compression to resist lateral movements of said means.

4. In combination, a vehicle body construction comprising in part, spaced upright walls rigid with the vehicle body, a substantially horizontal lower supporting plate connecting said upright walls, bumper and coupling means supported on said lower plate for movement relative thereto, said means being formed with upright walls located in spaced relation to said first mentioned upright walls, spaced stop shoulders on said upright walls limiting the movement of said means, plates removably secured to said upright walls between the stop shoulders, and non-metallic cushioning material secured to said plates and acting in shear to resist movements of the said bumper and coupling means.

5. In combination, a vehicle body construction comprising in part, spaced upright walls rigid with the vehicle body, a substantially horizontal lower supporting plate connecting said upright walls, bumper and coupling means supported on said lower plate for movement relative thereto, said means being formed with upright walls located in horizontally spaced relation to said first mentioned upright walls, plates removably secured to said walls, and non-metallic cushioning material secured to said plates and acting in shear to resist movements of the said bumper and coupler means, and independent stop means on said walls cooperating to limit movements of the bumper and coupling means whereby the shear strain on said non-metallic material will be limited.

6. In combination, a vehicle body construction comprising in part, spaced upright walls rigid with the vehicle body, a substantially horizontal lower supporting plate connecting said upright walls, bumper and coupling means supported on said lower plate for movement relative thereto, and non-metallic cushioning elements secured to said means and to said upright walls, said elements being located wholly at the side of said bumper and coupling means and acting in shear to resist longitudinal and angular movements of the said bumper and coupler means and acting in compression to resist lateral movements thereof.

7. In combination, a vehicle body construction comprising in part, a box-like housing rigid with respect to the vehicle body, upright walls forming the sides of the housing, a combined bumper and coupler means having a rear portion movably supported within the housing, and non-metallic cushioning elements interposed between and secured to said upright walls and rear portion, said elements acting in shear and compression to resist angular movements of the said bumper and coupler means.

8. In combination, a vehicle body construction comprising in part, a box-like housing rigid with respect to the vehicle body, upright walls forming the sides of the housing, a combined bumper and coupler means having a rear portion movably supported within the housing, non-metallic cush-

ioning elements secured to said upright walls and rear portion and acting in shear to resist movements of said bumper and coupler means, said housing and means being relatively so formed and arranged as to protect the cushioning element from injurious materials.

9. In combination, a vehicle body construction comprising in part, a box-like housing rigid with respect to the vehicle body, upright walls forming the sides of the housing, a combined bumper and coupler means having a rear portion movably supported within the housing, non-metallic cushioning elements secured to said upright walls and rear portion of said means, said elements acting in shear to resist movements of the said bumper and coupler means, and independent stop means on said housing and on said bumper and coupler means cooperating to limit the movements of said bumper and coupler means thereby limiting the shear strain that may be imposed upon the non-metallic material.

10. In combination, a vehicle body construction comprising in part, a one-piece housing having upright sides, a rear wall and a horizontal top wall, means substantially closing the housing and forming the bottom wall and front wall thereof, a combined bumper and coupler means having a rear portion extending into the housing through said first named means, and non-metallic elements joining said rear portion and housing together, said elements acting in shear to resist movements of the said bumper and coupler means.

11. In combination, a vehicle body having a pocket formed within the body at an end portion thereof, said pocket including substantially parallel plane side walls, a bumper element arranged in said pocket, and resilient means interposed between and secured to the bumper element and said side walls and so formed and arranged as to be subject to shear action upon movement of the bumper element relative to said side walls.

12. In combination, a vehicle body having a pocket at one end portion thereof, a bumper element arranged in said pocket and provided with side portions spaced from adjacent portions of said pocket, resilient means interposed between the bumper element and said adjacent pocket portions and secured to said bumper element and said portions and formed to shearingly resist movements of the bumper element relative to the body, and means in the pocket arranged to cooperate with the bumper element to limit movement of the said bumper element within the pocket.

13. In combination, a vehicle body having a pocket formed in one end portion thereof defined in part by side walls, a combined bumper and drawbar element arranged in the pocket with its side portions in spaced relation to said side walls, and means connecting the bumper element to said body comprising resilient units interposed between and connected to said side portions and side walls and so formed as to be subject to shear action in service.

14. In combination, a vehicle body including spaced sills, a combined bumper and drawbar element arranged between the sills and in spaced relation thereto, and means for connecting the said element to said sills comprising a resilient

unit interposed between said sills and said element and connected to each thereof and so formed and arranged as to be subject to shear action in service.

5 15. In combination, a vehicle body including spaced sills and a member extending transversely between and connected to said sills at points remote from their ends, a bumper element between the sills, resilient means connecting the bumper element and sills and so formed and arranged as to be subject to shear action in service, said member constituting a backing element for said bumper element to limit excessive movement of said bumper element in one direction.

10 15 16. In a vehicle body, longitudinal members spaced transversely of the car body, a member arranged within the body and connecting said longitudinal members, a bumper element arranged between the longitudinal members, and resilient means connecting the longitudinal members and bumper element and so formed as to be subject to shear action in service, said second named member constituting an abutment for said bumper element to limit excessive movement thereof in one direction.

20 17. In a vehicle body, longitudinal members spaced transversely of the car body, a member arranged within the body and connecting said longitudinal members, a bumper element arranged between the longitudinal members, resilient means connecting the longitudinal members and bumper element and so formed as to be subject to shear action in service, said second named member constituting an abutment for said bumper element to limit excessive movement thereof in one direction, and abutment means at the end of the body with which said bumper element is adapted to contact to limit movement of said bumper element in the opposite direction.

25 30 35 40 18. A bumper element for railway cars comprising a substantially closed box-like member having top, bottom, side and end walls, vertically spaced members projecting from one of said end walls and constituting top and bottom cover plates adapted to receive bumper blocks therebetween, and stop elements projecting from opposite end portions of the other end wall.

45 50 55 19. In a mine or similar rail car having a floor, side sills, and an end member connecting said side sills to form a frame, a combined bumper and draft element supported by said end member, and means for resiliently resisting buffing and draft forces to which the element is subjected, said means comprising resilient elements extending between the end portions of the sills and the adjacent portion of said element and retained in position in such a manner as to be subject to shearing action in service.

60 65 20. In a mine or similar rail car having a floor, side sills, and an end member connecting said side sills to form a frame, a combined bumper and draft element supported by said end member, and elastic cushioning material interposed between the side sills and adjacent end portions of said element; said material being so formed and arranged as to be subject to shearing action upon relative movement of the end member and element.

HERMAN H. PANCAKE.
